UNITED STATES PATENT OFFICE

DONALD G. SMELLIE AND HARRY B. WHITE, OF CANTON, OHIO, AND MARVIN E. NULSEN, OF ST. LOUIS, MISSOURI, ASSIGNORS TO THE HOOVER COMPANY, A CORPORATION OF OHIO

SUCTION CLEANER

Application filed July 12, 1929. Serial No. 377,642.

This invention relates to suction cleaners, and in particular to suction cleaners provided with positive agitating means of the type disclosed in our co-pending application, 5 Serial No. 80,731, filed January 12, 1926, of which the present application is a continuation in part.

The primary object of the present invention is to provide, in a suction cleaner, an arrangement of parts which will result in increased cleaning efficiency. A further object of the present invention is to provide, in a suction cleaner construction provided with positive agitating means, an arrangement of parts which will insure a minimum resistance to movement of the machine over the surface covering undergoing cleaning. A still further object is the provision of a suction cleaner construction in which the positive agitator is so arranged that the resistance to movement of the machine caused by the use of high vacuum is materially reduced. A still further object of the present invention is the provision of a metallic rotary agitator within the suction nozzle which will prevent undue displacement of the surface covering within the suction nozzle. Other and more specific objects of the invention will appear from the following detailed description, and the claims annexed thereto upon consideration thereof in connection with the appended drawing.

Referring now to the drawing, in which like reference characters refer to the same parts of the various views:

Figure 1 is a side view, partly in section, of a suction cleaner constructed in accordance with the present invention.

Figure 2 is a front elevation of the agitating unit shown in Figure 1.

In the drawing, the reference character 1 refers to a suction cleaner, constructed in accordance with the present invention, which comprises the usual motor casing 2 supported 45 upon a main casting 3 of unitary construction and providing a fan chamber 4, a suction nozzle 5, and an exhaust outlet 6. The main casting is supported upon the surface undergoing cleaning by front supporting 50 wheels 7-7, of which one is shown in the

drawing, and rear supporting wheels 8-8, the position of which relative to the cleaner, may be varied by means of the adjusting mechanism indicated generally by the reference character 9. The shaft 10 of the motor, 55 which is not shown in detail, projects downwardly from the motor casing 2 through the fan chamber 4 and into the suction nozzle 5, where it is provided at its end with a pulley 11 which functions as hereinafter described. 60 Positioned within the fan chamber 4, and carried by the motor shaft 10, is the fan 12, which functions, in the operation of the machine, to draw air from the suction nozzle 5, through the fan chamber 4, and exhaust same 65 through the exhaust outlet 6 into a receiving member attached thereto, indicated generally by the reference character 13. Positioned within the suction nozzle 5, upon a non-rotatable shaft 14, which is carried by the 70 main casting 3, is the rotary agitator member 15, disclosed in front elevation in Figure 2.

The agitator member 15 comprises a cylindrical body 16, the surface of which is extremely smooth, being preferably highly 75 polished. Positioned upon the cylindrical surface of the body 16, and extending helically therearound, are positive beating members indicated by the reference character 17, also of metal and extremely smooth. Secured to the agitator member 15 below the surface of the body 16, but extending thereabove, are the parallel brushes 18-18 which cooperate with the beaters 17 to agitate the surface covering, when the machine is in operation. End plates 19-19 are positioned at the ends of the agitating member and enclose the ends thereof, and, positioned approximately midway of the structure, is the pulley 20 which receives the driving belt 21 80 by which the rotary agitator member is driven from the driving pulley 11.

In the operation of a cleaner constructed in accordance with the present invention, the rotation of the suction fan 12 creates a reduced pressure within the suction nozzle 5, and the surface covering undergoing cleaning is lifted upwardly and contacts with the forward lip 21 and the rearward lip 22 of said nozzle. The cleaning air, passing under 100

the lips 21 and 22, serves to remove the foreign matter in the surface covering near the top thereof, and the greater the reduction of pressure within the nozzle 5 the more effective is the cleaning air. In the usual cleaner provided with the relatively wide suction mouth requisite to housing positive agitating means, the use of high vacuum is prohibited by reason of the undue displacement of the surface covering within the nozzle and between the lips 21 and 22, which results in a binding action and a prohibitive increase in the resistance to movement of the machine over the surface being cleaned. According to the present invention a third contacting means functioning to limit the upward displacement of the surface covering is positioned between the nozzle lips, in the form of the smoothly polished cylindrical body of the rotary agitator which extends substantially into the plane of the nozzle lips. The smooth surface of the cylindrical body is absolutely necessary to the invention, because a slightly rough surface on a body in rotary contact with the surface covering would result in undue wear to said covering, and it is necessary to avoid the placing of a prohibitive load upon the driving motor through the frictional resistance to rotation of the rotor. A surface even slightly rough would defeat the object of the present invention, namely the reduction in the resistance to movement of the machine, through the tendency to pull the cleaner over the surface in one direction, which would be the direction opposite to that in which the operator would wish it to move one-half of the time. The agitating elements 17 and the brushes 18, upon the surface of the body 16, serve to agitate the surface covering since they intermittently contact with it during the rotation of the element 15, but the normal position of said surface covering is determined by its line of contact with the major cylindrical portion of the surface of body 16.

We claim:

1. In combination, in a suction cleaner provided with a suction nozzle having spaced lips thereon, means to lift a surface covering undergoing cleaning into contact with said lips, a rotary agitator comprising a smooth substantially cylindrical body within said nozzle having an agitating element thereon, said cylindrical body projecting substantially into the plane of the nozzle lips.
2. In combination, in a suction cleaner provided with a suction nozzle having spaced lips thereon, and means to lift a surface covering undergoing cleaning against said lips, a metallic rotary agitator within the nozzle comprising a body with an agitating element thereon, said body being substantially cylindrical and arranged in said nozzle to extend substantially into the plane defined by the nozzle lips to contact with the lifted surface

covering and to define the limit to which the surface covering can be lifted.

3. In combination, in a suction cleaner provided with a suction nozzle having spaced lips thereon, and means to lift the surface covering undergoing cleaning against said lips, a driven rotary substantially cylindrical agitator within the nozzle having a smooth metallic surface extending substantially into the plane of the nozzle lips and contacting the surface covering to limit the upward displacement of said covering substantially to the plane of the nozzle lips, the surface of said agitator being provided with a protrusion forming an agitating element.

4. In combination, in a suction cleaner provided with a suction nozzle having spaced lips thereon, a driven rotary agitator within the nozzle comprising a substantially cylindrical body having a smooth surface and having rigid projecting elements thereon, said cylindrical body extending substantially into the plane of the nozzle lips and said projecting elements extending therebelow in some rotary positions of said agitator.

5. In combination, in a suction cleaner provided with a suction nozzle having lips defining a suction mouth, a driven rotary agitator within the suction nozzle, said agitator having a polished metallic surface extending substantially into the plane defined by the lips of the nozzle, a major portion of said metallic surface being continuous and acting to limit the extent to which a surface covering being cleaned will be drawn into the suction nozzle, and other portions of said surface extending radially beyond said major portion and effecting an agitation of the surface covering being cleaned.

6. In combination, in a suction cleaner provided with a suction nozzle having lips defining a suction mouth, a driven substantially cylindrical body substantially filling the suction mouth, and extending substantially into the plane defined by the nozzle lips and having a smooth surface for engagement with the surface covering being cleaned and rigid agitating elements on said cylindrical body.

7. In combination, in a suction cleaner provided with a suction nozzle having lips defining a suction mouth, a driven metallic substantially cylindrical member rotatably mounted within the suction mouth and extending substantially into the plane defined by the lips of the nozzle, said member being formed with helically extending rigid ridges for agitating the surface covering being cleaned.

8. In combination, in a suction cleaner provided with a nozzle having lips defining a suction mouth, a substantially cylindrical body having a smooth surface and beating elements positioned radially beyond said surface and a surface of reduced radius

positioned below said smooth surface adapted to function as a pulley, characterized by the fact that said body is positioned in said nozzle with said beating elements extending through the plane of said nozzle lips.

9. A suction cleaner comprising a prime mover, a suction creating device operatively connected thereto, a suction nozzle provided with spaced lips and operatively connected to said suction creating device, a rotary agitator mounted within said suction nozzle and operatively connected with said prime mover, said agitator comprising a smooth surfaced

cylindrical body and a series of agitating elements mounted thereon, said cylindrical body being positioned in said suction nozzle so that its bottom portion extends substantially into the plane defined by the nozzle lips, 70 said series of agitating elements being so arranged on said body as to provide surfaces on said body capable of contacting throughout their axial length with a surface covering undergoing cleaning.
